COIN CHUTE

Walter A. Tratsch and Bernhard Grunig,
Chicago, Ill.

Application March 14, 1935, Serial No. 11,103

2 Claims. (Cl. 194—98)

This invention relates to a coin chute.

It is an object of this invention to provide an improved game apparatus which is relatively simple and inexpensive in construction and efficient in use.

Another object of the present invention is to provide a coin chute embodying a new and improved visible display device for displaying a coin or token to view so that the owner or proprietor of the coin-controlled device with which the coin chute is associated may determine by inspection of the same whether or not a coin or token of the intended or proper denomination, etc., or a fraudulent substitute therefor, has been inserted into the coin chute to operate the same and the coin-controlled device associated therewith.

Another object of the present invention is to modify or construct the coin chute described and shown in the following patents: No. 1,908,380 granted May 9, 1933 to Walter A. Tratsch and No. 1,908,752 granted on May 16, 1933 to Louis M. Hall, so as to embody or incorporate into the same a visible coin or token display feature or device.

25 Other objects will appear hereinafter.

The invention consists in the novel combination and arrangement of parts to be hereinafter described and claimed.

The invention will best be understood by reference to the accompanying drawings, showing the preferred form of construction and in which:

Fig. 1 is a top plan view of the new coin chute;

Fig. 2 is a longitudinal sectional view on line 2—2 in Fig. 1;

Fig. 3 is a bottom plan view of the same;

Fig. 4 is a sectional detail view on line 4—4 in Fig. 1;

Fig. 5 is a sectional view similar to Fig. 4 but showing the parts in a different position;

Fig. 6 is a bottom perspective detail view;

Fig. 7 is a perspective view, partly in section of certain parts of the new coin chute;

Fig. 8 is a fragmentary top plan view of the cabinet of a coin-controlled amusement device showing the new coin chute in use; and

Fig. 9 is a sectional detail view taken on line 9—9 in Fig. 4.

A preferred form of the new coin chute is shown in the accompanying drawings, is therein generally indicated at 10, and includes a guide structure 11, and a coin slide 12 carried thereby; the guide structure 11 including a mounting or face plate 13 by means of which the coin chute 10 may be mounted in the wall of the cabinet

or casing 34 of a coin-controlled device, machine, or apparatus, as shown in Fig. 8.

Provided in the coin slide 12 is a coin-receiving aperture 27 and formed in the slide 12 at diametrically opposite points upon the periphery 5 of the coin aperture 27 a depressed portions or teeth 38 and 39 (Fig. 2) which function to move the coin or token disposed in the coin aperture 27 in opposite directions, as is disclosed in the aforementioned Tratsch and Hall patents. 10

Provided in the coin slide 12 is an elongated slot 21 (Fig. 9) and mounted in the guide structure 11 above the slide 12 is a stop 46 which includes a portion that projects or extends into the slot 21 (Figs. 4 and 5). 15

The present coin chute 10 includes latch dogs 35, 36 and 37 which are pivotally mounted on the guide structure 11 for engagement in the coin aperture 27 of the coin slide 12 so as to prevent operation of the coin slide 12 if no coin or 20 token, or if a coin or token or slug having a thickness or diameter less than that of the intended coin or token, or if an apertured or slotted slug, or the like is disposed in the coin aperture 27; this arrangement of the dogs 35, 25 36 and 37 and the function thereof being substantially the same as that disclosed in the above-named Tratsch and Hall patents.

Mounted on, or formed as a part of the upper wall of the guide structure 11, as may be desired, 30 is an annular member or ring 13 in which is provided a coin displaying sight opening 14 and formed in a horizontal shelf 16 which is suspended from the guide structure 11 below the coin slide 12, by means of a bracket or support 15, 35 30 is a coin display pocket 17 (Fig. 2), this display pocket 17 being disposed in a registration with the sight opening 14.

The bracket or support 15 forms the bottom wall of the coin display pocket 17 (Fig. 2) and 40 is slidably mounted upon the bracket 15 below the coin display pocket 14—17 and below the shelf 16 is a slide bar 18 in which is provided a coin discharge opening 19; and carried by this slide bar 18 and projecting upwardly therefrom, 45 adjacent the inner end of the same, is a pin 20, this pin 20 projecting into the slot 21 which is formed in the coin slide 12.

Having one end attached to the slide bar 18, as at 22, and having its other end attached to 50 the bottom wall 15 of the coin display pocket 14—17, as at 23, is a resetting spring 24 by means of which the slide bar 18 is normally urged (right to left, Figs. 1, 2 and 3) so as to dispose the coin discharge aperture 19 therein in 55

registration with the coin display pocket 14-17; the slide bar 18 being stopped in this position by means of a pin 25 which is attached to the guide structure 11, this pin 25 projecting downwardly through a slot 26 which is formed in the slide bar 18 (Fig. 3).

Provided in the coin slide 12 is a sight opening 28 (Fig. 7), and the coin slide 12 is normally urged (right to left, Fig. 7), by its resetting spring 47, so as to dispose the sight opening 28 formed therein in registration with the coin display or sight opening 14 which is formed in or upon the top wall of the guide structure 11.

Mounted on the guide structure 11, above the slide 12, is a magnet 42 and likewise mounted in the guide structure 11 above the slide 12 is a stop 46 which has an end portion 41 which depends or extends into the slot 21 in the slide 12.

Having one end portion 29 attached to the annular member 13 and having its other end portion or arm 30 projecting downwardly through the coin display or sight opening 14 is a spring 31.

Provided in the upper surface of the shelf 16 (Figs. 5 and 9) is a depressed ledge or pocket 48.

Operation

The coin slide 12 is normally disposed, by the action of the resetting spring 47, in coin-receiving position with the sight opening 28 in the coin slide 12 disposed in registration with the sight opening 14, as in Figs. 1, 2 and 3, and when a coin is inserted into the coin aperture 27 of the coin slide 12 and the latter is pushed inwardly (left to right, Figs. 1, 2 and 3), the coin or token disposed in the coin aperture 27 of the slide 12 is carried by the slide 12 along the upper surface of the bottom wall 32 of the guide structure 11, and falls from the latter into the pocket 48 which is formed 40 in the upper surface of the shelf 16, (into dotted line position "A", Fig. 5) whereupon further movement of the coin slide 12 causes the coin or token disposed in the coin aperture 27 of the coin slide 12 to be angled downwardly off the front or 45 inner end of the shelf 16 (into dotted line position "B", Fig. 5); and further inward movement of the coin slide 12 and the slide bar 18 urges the coin or token onto the upper surface of the rear portion of the slide bar 18, wherein the coin or token is deposited in dotted line position "C", Fig. 5.

The coin or token is thus deposited on the upper surface of the slide bar 18, and as the coin slide 12 is pushed inwardly (left to right, Figs. 1, 2, 3 and 6), the shoulder 33 formed in the coin slide 12 engages the pin 20, which is carried by the slide 18, whereupon the slide 12 and the slide 18 move together as a unit (left to right, Fig. 7), and when the slides 12 and 18 are returned to 60 their normal or initial positions, the coin or token which has previously been deposited on the upper surface of the lower slide 18 falls into the coin aperture 19 of the slide 18, wherein it is exposed to view through the registered sight openings 14 and 28.

A magnetic token or disc is prevented, by the coaction of the stop 41-46 and magnet 42, from entering the display pocket 14-17 since if a magnetic disc or token is inserted into the coin aperture 27 and the slide 12 is pushed inwardly the magnet 42 will hold the magnetic disc up in the plane of the coin slide 12 so that it will abut the stop 41 and be prevented from falling onto the shelf 16 and into the pocket 48 (into position 75 "A" Fig. 5).

The spring 31 retains a coin in the display pocket 14-17 and against dislodgment therefrom if the coin chute and associated apparatus are shaken or inverted from their normal position, thereby preventing fraudulent dislodgment of the coin from the coin display pocket 14-17.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

We claim:—

1. A coin chute comprising a coin slide having a coin-receiving or token-receiving aperture formed therein; a guide structure for said coin slide having means to support a coin or token in said aperture when the coin slide is moved from a coin receiving position to a coin discharging position; said guide structure having a coin or token display pocket formed therein for the reception of a coin or token discharged from the said coin aperture of said coin slide; said coin slide having a sight opening formed therein and disposed in registration with said display pocket when said coin slide is disposed in its normal or coin receiving position; a second slide carried by said guide structure and having a coin-receiving or token receiving aperture formed therein; said guide structure having means for guiding the second-named slide in a plane substantially parallel to, but below, the plane of movement of said first-named slide; said aperture in the second-named slide being disposed in registration with said display pocket and with said sight opening in said first-named slide when said slides are disposed in their normal or initial positions whereby a coin or token in said aperture of said second-named slide will be visible for inspection; said guide structure having means to support a coin or token in the aperture of said second-named slide when the aperture in said second-named slide is in registration with said display pocket and said sight opening; means coacting with said first-named slide, when the latter is moved away from its initial position, to move said second-named slide whereby a coin in the aperture of said second-named slide will be discharged therefrom and a coin carried in the aperture of said first-named slide will be discharged therefrom into said display pocket and will rest upon an end portion of said second-named slide; and means for returning said slides to normal position whereby the coin resting upon the end portion of said second-named slide will drop into the aperture of said second-named slide.

2. A coin chute comprising a coin slide having a coin-receiving or token-receiving aperture formed therein; a guide structure for said coin slide having means to support a coin or token in said aperture when the coin slide is moved from a coin receiving position to a coin discharging position; said guide structure having a coin or token display pocket formed therein for the reception of a coin or token discharged from the said coin aperture of said coin slide; said coin slide having a sight opening formed therein and disposed in registration with said display pocket when said coin slide is disposed in its normal or coin receiving position; a second slide carried by said guide structure and having a coin-receiving

- or token receiving aperture formed therein; said 5
guide structure having means for guiding the
second-named slide in a plane substantially parallel to, but below, the plane of movement of said
first-named slide; said aperture in the second-named slide being disposed in registration with
said display pocket and with said sight opening
in said first-named slide when said slides are disposed in their normal or initial positions whereby
10 a coin or token in said aperture of said second-named slide will be visible for inspection; said
guide structure having means to support a coin or token in the aperture of said second-named slide when the aperture in said second-named slide is in registration with said display pocket and said sight opening; means including a lost
15 motion connection coacting with said first-named slide, when the latter is moved away from its initial position, to move said second-named slide whereby a coin in the aperture of said second-named slide will be discharged therefrom and a 5
coin carried in the aperture of said first-named slide will be discharged therefrom into said display pocket and will rest upon an end portion of said second-named slide; and means for returning said slides to normal position whereby the coin 10 resting upon the end portion of said second-named slide will drop into the aperture of said second-named slide.

WALTER A. TRATSCH.
